US00D776610S

(12) **United States Design Patent** (10) Patent No.: **US D776,610 S**
Nommensen et al. (45) Date of Patent: ** Jan. 17, 2017

(54) **BATTERY**

(71) Applicant: **Briggs & Stratton Corporation**,
Wauwatosa, WI (US)

(72) Inventors: **James Nommensen**, Oak Creek, WI
(US); **Paul D. Kluck**, Belguim, WI
(US); **Matthew Markowski**,
Wauwatosa, WI (US); **Robert Koenen**,
Pewaukee, WI (US); **Dale S. DiJulio**,
Saukville, WI (US); **Bart Mayer**, Fond
du Lac, WI (US); **Brian D. Neeley**,
West Bend, WI (US)

(73) Assignee: **Briggs & Stratton Corporation**,
Wauwatosa, WI (US)

(**) Term: **14 Years**

(21) Appl. No.: **29/488,711**

(22) Filed: **Apr. 22, 2014**

(51) LOC (10) Cl. **13-02**

(52) U.S. Cl.

(57) **CLAIM**

We claim the ornamental design for a battery, as shown and described.

DESCRIPTION

FIG. 1 is a front perspective view from above of the battery; FIG. 2 is a front perspective view from below thereof; FIG. 3 is a rear perspective view from above thereof; FIG. 4 is a rear perspective view from below thereof; FIG. 5 is a detail view of a portion of the battery in FIG. 4; FIG. 6 is a front view of the battery; FIG. 7 is a rear view thereof; FIG. 8 is a detail view of a portion of the battery in FIG. 1; FIG. 9 is a right side view thereof; FIG. 10 is a left side view thereof; FIG. 11 is a detail view of a portion of the battery in FIG. 10; FIG. 12 is a top view of the claimed design of the battery; and, FIG. 13 is a bottom view thereof.

The broken lines shown are for the purpose of illustrating environmental structure, and form no part of the claimed design.

1 Claim, 13 Drawing Sheets
